UNITED STATES PATENT OFFICE.

CHARLES REMHOF, OF BROOKLYN, NEW YORK.

SYRINGE.

933,490.

Specification of Letters Patent. Patented Sept. 7, 1909.

Application filed March 18, 1908. Serial No. 421,777.

To all whom it may concern:

Be it known that I, CHARLES REMHOF, a citizen of the United States, and a resident of Brooklyn, Kings county, New York, have 5 invented certain Improvements in Syringes, of which the following is a specification.

This invention relates to certain improvements in syringes, and more particularly to that class of such devices which are especially designed and adapted for vaginal and other similar uses, and the object of the invention is to provide a device of this general character of a simple and comparatively inexpensive nature, and of a strong and compact construction, permitting the improved syringe to be readily packed within a small compass so as to be capable of being conveniently put out of the way when not required for use.

10 The invention consists in certain novel features of the construction, and combinations and arrangements of the several parts of the improved syringe, whereby certain important advantages are attained, and the 15 device is rendered simpler, cheaper and otherwise better adapted and more convenient for use, all as will be hereinafter fully set forth.

20 The novel features of the invention will be carefully defined in the claims.

In the accompanying drawings, which serve to illustrate my invention—Figure 1 is a perspective view showing a syringe embodying my improvements; Fig. 2 is a sectional view taken axially through the syringe, the flexible tubing and discharge nozzle being broken away for lack of space; Fig. 3 is a sectional view, similar to Fig. 2, but showing the improved syringe compacted, the flexible tubing and discharge nozzle being disconnected from the body portion of the device and packed within the barrel or cylinder thereof; Fig. 4 is another 25 sectional view, similar to Fig. 2, but showing the body portion of the improved syringe compressed as it appears when operated to discharge the contained fluid from its barrel or cylinder, and Fig. 5 is a sectional view taken transversely through the cylinder or barrel of the syringe and illustrating a modified form of the device wherein said cylinder or barrel is made flattened in cross section.

30 As shown in Figs. 1 to 4, the improved syringe is constructed with a cylindrical body portion formed from a lower or base member 1, and an upper or actuating mem-

ber 2, said members 1 and 2 being made from thin metal tubing and having their interiors adapted for communication to produce a liquid chamber within said cylindrical body portion. The lower or base member 1 is formed from tubing with an exterior diameter as nearly like the interior diameter of the upper or actuating member 2 as is practicable, and the side walls of said 35 lower or base member 1, are adapted to fit snugly within and slide telescopically flush upon and along the side walls of the upper or actuating member 2 in order to permit the body portion or barrel formed from said 40 members to be longitudinally compressed or extended in the operation of the syringe for discharging liquid from or drawing the same into the liquid chamber produced within said body portion or barrel, as will 45 be hereinafter explained. This construction of the members 1 and 2 insures accurate and flush contact of the side walls of the members, when the body portion or barrel is compressed, as shown in Fig. 4, throughout 50 substantially the whole extent to which said members are overlapped, and thereby permits of dispensing altogether with the employment of extraneous guiding means, and affords the maximum pumping capacity 55 consistent with the length of the body portion or barrel when compressed. The structure is, moreover such that the upper or actuating member 2 affords a cap or closure for the upper open end of the lower or base 60 member 1, and thereby affords a material simplification of the device.

3 and 4 represent end members or valve casings which are secured upon the opposite open ends of the respective lower and upper members 1 and 2, said end members 3 and 4 being herein shown provided with screw connections with said tubular members 1 and 2, although it will be evident that the present invention is not limited to the employment of said screw connections and that any other preferred attachment may be substituted therefor. The upper end member 4, however, is preferably adapted for ready detachment from the upper tubular member 2, 70 in order that access may be afforded to the interior of the barrel or body portion for purposes to be hereinafter explained.

At the overlapping ends of the telescoping tubular members 1 and 2 of the device I 75 provide a packing to prevent excessive leakage of the fluid between the parts, and I

- have herein shown this packing in the form of an annular band or gasket 6 of rubber or other suitable material which is held in place in a seat or channel 5 extended around the 5 upper end of the lower tubular member 1, said channel being formed by swaging the material from which said member is formed inwardly in a manner which will be readily understood by inspection of the drawings.
- 10 The lower end member or casing 3 is formed with a passage 7 extended centrally through it, the lower end of said passage being expanded, and the wall of said end member or casing being notched at suitable intervals as shown at 10, to afford access to the said expanded lower end of passage 7, when the syringe is rested upon the bottom of a vessel containing a supply of liquid, as shown in Fig. 4, so that the liquid contained 15 in said vessel may enter said expanded lower end of passage 7, and the upper end of said passage 7, where it communicates with the interior or bore of the cylindrical body portion of the device is provided with a valve seat adapted to be engaged by a valve 8 provided with a check 9 for limiting its movement and so arranged as to permit free entry of liquid into the bore of the body portion through said passage 7, while being adapted 20 to effectively prevent, by its engagement with said valve seat, the outflow of liquid from the body portion through said passage.
- 25 The detachable upper end member or casing 4 is provided with a nipple 11 extended from it and adapted for detachable connection with a flexible tube 15 of rubber or the like, the extremity of which is likewise adapted for detachable connection with a discharge nozzle 16 in a well known way,
- 30 and a passage is provided within said nipple 11, with its lower end communicating with the interior or bore of the body portion of the device for the discharge of liquid therefrom to the flexible tube 15, which passage 35 has a valve seat adapted to be engaged by a valve 12, the movement of which is also limited by a check 14 in a well known way. This valve 12 is adapted, by engagement with its seat, to prevent the backflow of 40 liquid or air from the tube 15 into the interior or bore of the cylindrical body portion of the syringe, but is adapted to permit the free flow of the liquid from said body portion through said tube 15 in order that 45 the same may be discharged at the nozzle 16. The valved inlet and valved outlet of the body portion being, by this construction, located adjacent to the opposite ends of the device, it will be evident that occlusion of said 50 outlet and inlet during the telescopic movement of the members from which the body portion is produced is effectively avoided and a maximum discharge capacity is afforded.
- 55 At the lower part of the cylindrical body

portion of the syringe is arranged an annular flange 17, projecting around the lower end of the lower tubular member 1, and herein shown as formed integrally with the lower end of said member 1 by pressing the 70 material from which said member is formed outwardly, and this flange forms an abutment or shoulder against which is rested the lower end of a spiral spring 18, which encircles said lower tubular member above said shoulder or abutment and has its upper end engaged with a similar abutment or shoulder 19 produced at the lower end of the upper tubular member 2 of the device, and which is formed, as herein shown, of an integral 75 annular flange bent or swaged outwardly around the said lower end of the member 2. By this arrangement of the parts it will be seen that the tension of the spring 18 is normally exerted to hold the two tubular members 1 and 2 of the body portion slid endwise one upon the other in such a way as to extend or elongate said body portion as shown in Figs. 1, 2 and 3, the liquid chamber within said body portion being thus given a 80 greater capacity than that of either of its members separately considered, and said spring being coiled upon the exterior of the device is readily accessible for purposes of repair, and is not liable to be corroded by 85 the liquid in connection with which the improved syringe is used, as would be the case were said spring arranged within the liquid chamber. In order to prevent separation of 90 said tubular members 1 and 2 from each other I provide a securing device connected at one end with one of said members and having its opposite end adapted for sliding engagement with the other member in such manner as to effectively prevent dislocation 95 of the parts while permitting the sliding movement of the members relative to each other which is necessary for the operation of the improved syringe. This securing device, as herein illustrated, is in the form of a 100 narrow strip 20 of metal, extended parallel with and closely adjacent to the lower tubular member 1, and preferably inclosed within the spiral spring 18 so as to be protected 105 thereby, the lower extremity of said strip 110 being connected with said lower tubular member 1 near the lower end of the latter, while the upper end of said strip is passed through and adapted for sliding engagement in an aperture 21 produced in the annular flange 19 at the lower end of the upper tubular member 2, and has a bent extremity 115 22 which forms an enlargement adapted for engagement against the upper surface of said flange 19 in such a manner as to limit 120 the longitudinal extension of the body portion of the device and prevent separation of the members from which the same is formed.

125 In the use of the device, the flexible tube 15 and nozzle 16 being attached to the body 130

portion of the syringe, the lower end of said body portion, comprising the lower end member or casing 3, is dipped within the liquid contained in a suitable vessel, whereupon by pressing the upper member 2 downward upon member 1 against the tension of the spring, the air will be discharged from the body portion of the device, and upon permitting said spring to react and lift said upper member, a portion of the liquid contained in said vessel will be drawn through the ports 10 and passage 7 into said body portion to replace said discharged air. By repeating this operation until the body portion shall have become filled with the liquid it is evident that such liquid will thereafter be discharged from the body portion through the flexible tube and nozzle 16 as in the well known bulb syringe.

When the device is not required for use, the upper end member or casing 4 may be detached to afford access to the interior or bore of the body portion, which thereupon serves as a receptacle for the flexible tube and nozzle 16 upon the disconnection of these parts at the nipple 11, whereby as indicated in Fig. 3, the character of the device is to a great extent disguised, while at the same time the tubing and nozzle are ready at hand for use.

From the above description it will be seen that the improved syringe constructed according to my invention is of an extremely simple and comparatively inexpensive construction and is especially well adapted for use by reason of its compact and durable construction, and it will also be obvious from the above description that the device is susceptible of some modification without material departure from the principles and spirit of the invention and for this reason I do not desire to be understood as limiting myself to the precise form and arrangement of the several parts herein set forth in carrying out my invention in practice. Nor do I desire to be understood as limiting myself to the employment of any special material for the construction of the improved syringe, since it is evident that the invention is not limited in this respect. Nor is

the cylindrical form of the body portion at all essential to the invention since, when desirable, the telescoping members 1 and 2 may be made flattened as shown in Fig. 5, or may have other cross sectional forms with good results.

Having thus described my invention, what I claim and desire to secure by Letters Patent is—

1. A syringe having a body portion comprising two tubular members arranged for telescopic sliding movement one within the other, a securing device formed of a strip having one end attached to one of the tubular members, and having its opposite end extended lengthwise along the body portion and engaged for sliding movement in an aperture of the other tubular member to limit the telescopic sliding movement thereof, and a spring coiled around the body portion outside of said strip and having engagement at its opposite ends with the respective tubular members to hold the same normally in one position while permitting telescopic movement of such members against the tension of said spring, said body portion having an inlet and an outlet, and valves controlling the inlet and outlet of the body portion.

2. A syringe having a body portion provided with two members of substantially like diameters having adjacent open ends fitted to slide telescopically one within the other, the interiors of said members being in communication and forming an unobstructed liquid chamber extended from end to end of the body portion, valves controlling the admission and discharge of liquid to said chamber, and closures for the opposite ends of the body portion, one of said closures being removable to afford access to the liquid chamber for the insertion of nozzles or the like therein.

In witness whereof I have hereunto signed my name in the presence of two subscribers.

CHARLES REMHOF.
